UNITED STATES PATENT OFFICE

ARVID ERICSSON, OF CHICAGO, ILLINOIS, ASSIGNOR TO UNION SPECIAL MACHINE COMPANY, OF CHICAGO, ILLINOIS, A CORPORATION OF ILLINOIS

LOOP RETAINER FOR SEWING MACHINES

Application filed June 7, 1927. Serial No. 197,068.

The invention relates to new and useful improvements in loop retainers for sewing machines, and more particularly to a four-motion loop retainer adapted to cooperate with a four-motion thread carrying looper for holding the needle thread loop back on the looper to insure proper stitch formation.

An object of the invention is to provide a loop retainer which is so shaped and so operated as to hold the needle thread loop properly positioned so that the needle will enter the thread triangle in the stitch formation, even though the fabric remain stationary during successive stitch formations, or is moved in a direction parallel with the plane of oscillation of the looper as it moves into and out of the needle thread loop.

A further object of the invention is to provide an actuating mechanism for a loop retainer of the above character, wherein the loop retainer is moved lengthwise of the looper by an actuating member oscillating with the looper, and wherein said loop retainer has a different timing in the movement imparted thereto than that given the looper.

A still further object of the invention is to provide a retainer operating mechanism of the above type, wherein the retainer is moved laterally of the looper by means independent of the looper actuating mechanism.

These and other objects will in part be obvious and will in part be hereinafter more fully disclosed.

In the drawings which show by way of illustration one embodiment of the invention—

40 Figure 1 is a view partly in section and partly in side elevation, showing a portion of a sewing machine embodying my improvements;

Fig. 2 is a sectional view on the line 2—2 of Fig. 1;

45 Fig. 3 is a view partly in section and partly in end elevation of a portion of the sewing machine, the end cap of the work support being removed to show the looper and retainer;

Fig. 4 is a plan view showing the looper, the retainer and the immediate supporting and actuating mechanisms therefor in plan, the looper and retainer being positioned as shown in Fig. 3;

55 Fig. 5 is a view in end elevation, showing the needle, the looper and the retainer, and the means for oscillating the loop retainer, the looper being shown fully retracted;

Fig. 6 is a plan view of the parts shown in Fig. 5;

60 Fig. 7 is a view similar to Fig. 5, but showing the retainer as positioned so as to hold the needle thread loop and position the same for the entrance of the needle into the thread triangle;

65 Fig. 8 is a plan view of the parts as positioned in Fig. 7;

70 Fig. 9 is a perspective view of the loop retainer;

Fig. 10 is a detail in section showing the manner of supporting the retainer finger;

75 Fig. 11 is a detail in front elevation showing the needle, looper and retainer at the time when the needle point is passing between the looper thread and the body of the looper, and

Fig. 12 is a plan view of the parts shown in Fig. 11.

80 Fig. 13 is a view partly in section and showing more or less diagrammatically the position of the needle thread and looper thread, with the needle all the way up and the looper at the forward end of its stroke.

85 Fig. 14 is a similar view but showing the needle about to enter between the looper thread and the body of the looper, with the looper thread and needle thread held by the spreader.

90 Fig. 15 is a view showing the needle all the way down and the looper at the rear end of its stroke.

95 Fig. 16 is a view showing the needle on its upward movement and the looper as having moved into the needle thread loop.

The invention is directed broadly to a retainer and an actuating mechanism therefor, which retainer is adapted to hold the needle thread loop back on the looper to insure the entrance of the needle into the

100

thread triangle in the stitch formation. It is well known that the feed when transverse of a thread carrying looper, aids in the spreading of the triangle for the needle to enter. When a fabric is moved in a direction parallel with the plane of oscillation of the looper, it has no movement given thereto, then it is more difficult to bring about a proper concatenation of the needle thread loop with the looper thread loop. The thread carrying looper is of the usual type, and has four motions imparted thereto; an oscillating movement into and out of the needle thread loop and a lateral or needle avoiding movement. The invention is entirely in the loop retainer and the actuating mechanism therefor. The loop retainer is mounted so as to oscillate in a plane parallel with the plane of oscillation of the looper, but it has a different timing in its movement, so that it will engage and move the needle thread loop back on the looper at the proper time, and so that it will release the looper thread loop to permit the loop to be shed from the looper and moved to a position to engage the next needle thread loop. The oscillating movements of the loop retainer are derived from the shaft which supports and oscillates the looper. This is accomplished by mounting a cam on the shaft, and providing yoke arms which cooperate with the cam and which move the loop retainer. The loop retainer is moved laterally across the looper so as to engage the needle thread loop, and laterally away from the looper so as to release it. This is accomplished, in the present embodiment of the invention, by mounting the retainer on a shaft which is independent of the looper supporting shaft, and moving said retainer supporting shaft endwise by a connection with the usual feed bar of the machine.

Referring more in detail to the drawings, my improvement resides in a stitch forming mechanism including a needle 1, a looper 2 and a needle thread loop retainer 3. The needle thread is indicated at *n* and the looper thread at *l*. These elements are shown as embodied in a machine for sewing on buttons. The construction of the button sewing machine has not been illustrated in the drawings, as the invention is equally adapted to other types of machines. The features of the button sewing machine presented in the drawings are fully shown and described in my co-pending application Serial No. 192,249, filed May 18, 1927. The needle is vibrated laterally so as to enter first one eye and then another of the button. The fabric does not move during the forming of the stitches; therefore, there is no feed of the material to aid in the opening of the thread triangle to insure proper stitch formation. The loop retainer positions the

needle thread loop on the looper well back on the looper, and the shank of the loop at one side of the looper, to a slight extent, and thus it is that the needle point, in its next descent, although the fabric has not been moved, will pass between the shank of the needle thread loop and the body of the looper.

The machine as illustrated in the drawings, includes a work supporting cylindrical arm 4 carrying a throat plate 5 having an opening 6 therethrough, through which the needle passes. The looper 2 is provided with an eye 7 adjacent the point thereof, and an eye 8 at its heel, and with the usual thread groove. The looper is also provided with a notch 9 in its upper face in the region where the retainer passes across the looper to hold the needle thread loop back on the looper. The looper is mounted on a shaft 10 which extends lengthwise of the work supporting arm 4. On the end of the shaft, is a sleeve which is fixed thereto, and this sleeve carries a head 11. A carrier 12 for the looper is mounted on this head. The carrier has a center rod which extends into the sleeve and the carrier fits snugly up against the head. It is held against the head and in adjusted positions thereon, by a screw 13 passing through a slot 14 and threaded into the head. The looper is formed integral with a shank portion 15, and said shank is secured to the carrier 12 by means of a screw 16 passing through a slot 17 in the shank of the looper. The carrier has a recess 18 in the face thereof in which the shank 15 fits, and this provides a rigid holding means for the looper. As the shaft oscillates, it will oscillate the looper, and as the shaft moves endwise, it will move the looper laterally, giving a needle avoiding movement thereto.

The loop retainer 3 is mounted on a retainer support which consists of a sleeve 19, an elbow arm 20 formed integral therewith, and a cam arm 21, likewise formed integral with the sleeve 19. The retainer 3 fits in a socket 3^a in the outer end of the elbow arm 20, and is detachably and adjustably held therein by a set screw 3^b. The sleeve 19 is mounted on a rod or shaft 22. Said rod or shaft carries a collar 23 which is fixed thereto. The sleeve is freely mounted on the shaft so that it can oscillate thereon. It is held from endwise movement, however, on the shaft or rod 22, by means of a nut 24 with which is associated a lock nut 25. This rod or shaft 22 extends through a suitable journal bearing on the work supporting arm 4. In a button sewing machine, there is no feed, as the material remains stationary during the formation of the stitches. The feed bar, however, remains on the machine, as shown in the drawings, and is indicated at 26. This feed bar is given the usual endwise

movement. Fixed to the feed bar is a yoke 27. The shaft 10 passes freely between the arms of the yoke. The yoke is rigidly mounted at its lower end on the rod or shaft 22, and is held thereon by a nut 28. When the feed bar moves endwise through the yoke 27, it will impart an endwise movement to the rod 22.

Mounted on the looper shaft 10 is a cam 29. This cam is located between the elbow arm 20 and the cam arm 21. The cam arm 21 continuously bears against this cam 29. The elbow arm between the sleeve and the elbow, bears against this cam 29. The active portion of the cam 29 engaging the elbow arm is indicated at 30, and the active portion of the cam 29 engaging the cam arm 21 is indicated at 31. The cam 29 between the active portions 30 and 31, is provided with a concentric face. When the concentric face engages the cam arm 21, the retainer will be held at a dwell as shown in Fig. 5. During this time, the active portion 30 is moving along the elbow arm in the region between the elbow and the retainer, and will prevent any overflow of the retainer (see Figures 5 and 7). When the active portion 30 of the cam 29 engages the elbow arm, it will swing the retainer to the right as viewed in Fig. 3, and the active portion 31 of the cam 29 will move relative to the cam arm to permit this movement of the retainer.

The parts are timed so that the following movements take place. The looper moves forward into the needle thread loop and then comes to a slight dwell, after which it is retracted from the needle thread loop. While in the needle thread loop, it is moved laterally for its needle avoiding movement, and this positions the looper so that the needle point will pass alongside of the looper on the opposite side of the looper from which the needle is located when the looper takes the needle thread loop. This is the normal operation of a thread carrying looper. The retainer, when the looper is at the forward end of its stroke and fully into the needle thread loop, lies in front of the needle thread loop on the looper, and the looper thread running from the end of the looper to the material. The looper, at this time, is moved laterally, and the retainer has been given only a portion of its lateral movement. It is now moved across the looper and lengthwise of the looper during the retracting movement of the looper, and when so moved, it will come into engagement with the looper thread running from the eye of the looper to the fabric and the needle thread loop on the looper. The loop retainer is curved on its face as indicated at 3^b in the drawings, and as it moves against the looper thread and the needle thread loop, the needle thread loop will slide back on the curved face of the retainer, and so will the looper thread. As a

result, the looper thread is positioned well back on the retainer, although the point at which the looper thread and the needle thread loop are anchored in the material is at the point indicated at α in Fig. 12, which is the previous stitch puncture. The needle is indicated at 1, and when it passes down through the fabric, the point will pass between the looper thread indicated at 7 in this figure, and the body of the looper. The face 2^a of the looper adjacent the needle is cut away so as to provide a clearance for the needle, and this insures that the needle will, with certainty, pass into the thread triangle formed by the looper thread, the needle thread loop and the body of the looper. When the needle is vibrated laterally for its next stitch so as to enter the fabric at α in Fig. 12, then of course, it will, with certainty, pass into the thread triangle therefor. The loop retainer operating upon the needle thread loop to hold it well back on the looper, and operating upon the looper thread to hold it well away from the body of the looper, insures a perfect stitch formation, even though there is no movement of the fabric, and the needle is reciprocated so as to enter the material at different positions in a line substantially parallel with the plane of oscillation of the looper. After the needle point is well into the looper thread loop, the retainer has no further movement lengthwise of the looper during its retracting stroke. This is because the concentric portion on the controlling cam 29 comes into engagement with the cam arm 21. The retainer, however, moves laterally during this completion of the retraction of the looper after the needle point has passed the shank of the looper thread loop. This lateral movement of the retainer in a direction away from the retainer, causes the needle thread loop to be released, so that it can slide along the looper and off from the point of the looper.

From the above, it will be apparent that I have provided an operating mechanism for a loop retainer, wherein the loop retainer is oscillated by the oscillating movements imparted to the looper supporting shaft, but these movements imparted to the retainer are modified and changed as to their timing through the controlling cam working in conjunction with the elbow arm and cam arm which are rigid with the retainer. The lateral movements of the retainer are derived from the feed bar in the present embodiment of the invention, and this is entirely independent of the looper supporting shaft. It is true that this feed bar does not feed the material in a button sewing machine, because the material is not to be fed. Any other reciprocating bar may be used for imparting the lateral movements to the retainer, but it should be a bar which has

substantially the timing of the feed bar in its endwise movements. The essential feature is that the retainer shall have a movement laterally across the looper so as to engage the needle thread loop, and away from the looper to release the needle thread loop, all in the proper timing to permit the needle to properly pass the shank of the needle thread loop, and permit the needle thread loop to be shed from the looper.

While I have described my stitch forming mechanism with an improved loop retainer as particularly adapted to use in a machine for sewing on buttons, and wherein the needle is vibrated laterally, it will be understood, of course, that it may be used in other types of machines, and will be of particular value in a machine where the feed is in a direction parallel with the plane of oscillation of the looper, so that the movements of the fabric cannot be utilized in the opening of the thread triangle for the needle.

It is obvious that minor changes in the details of construction and arrangement of the parts may be made without departing from the spirit of the invention as set forth in the appended claims.

Having thus described the invention, what I claim as new and desire to secure by Letters-Patent, is—

1. The combination of a needle, a thread carrying looper cooperating therewith, a support for said looper adapted to oscillate and move endwise, a retainer for engaging and holding the needle thread loop back on the looper, an actuating member mounted on said looper support, and devices cooperating therewith for moving said retainer lengthwise of the looper, and means for moving said retainer laterally of the looper.

2. The combination of a needle, a thread carrying looper cooperating therewith, a support for said looper adapted to oscillate and move endwise, a retainer for engaging and holding the needle thread loop back on the looper, an actuating member mounted on said looper support, devices cooperating therewith for moving said retainer lengthwise of the looper, and means for moving said retainer laterally of the looper, said last-named means being independent of the looper support.

3. The combination of a needle, a thread carrying looper cooperating therewith, a support for said looper adapted to oscillate and move endwise, a retainer for engaging and holding the needle thread loop back on the looper, an actuating member mounted on said looper support, devices cooperating therewith for moving said retainer lengthwise of the looper, and means for moving said retainer laterally of the looper, said devices for oscillating the retainer being constructed so as to positively move the retainer and impart a different movement

thereto than that given to the looper by the looper support.

4. The combination of a needle, a thread carrying looper, a support for said looper adapted to oscillate and move endwise, a retainer, an independent support for the retainer adapted to oscillate and move endwise, means carried by the looper support for oscillating the support for the retainer, and means independent of the looper support for moving the support for the retainer endwise.

5. The combination of a needle, a thread carrying looper, a support for said looper adapted to oscillate and move endwise, a retainer, an independent support for the retainer adapted to oscillate and move endwise, means carried by the looper support for oscillating the support for the retainer, means independent of the looper support for moving the support for the retainer endwise, said means for oscillating the retainer including a controlling cam, and devices cooperating therewith for imparting a positive movement to the retainer which is different in character from the oscillation imparted to the looper by the looper support.

6. The combination of a needle, a thread carrying looper, a support for the looper adapted to oscillate and move endwise, a retainer, an independent support for the retainer substantially parallel with the support for the looper, means independent of the looper support for moving said support for the retainer endwise, a controlling cam carried by the looper support, said retainer support including an elbow arm cooperating with said cam at one side thereof, and a cam arm cooperating with said cam at the other side thereof, whereby said retainer support is given a positive oscillation of a different character from the oscillations imparted to the looper or the looper support.

7. The combination of a needle, a thread carrying looper, a support for the looper adapted to oscillate and move endwise, a retainer, a support for the retainer adapted to oscillate and move endwise, means carried by the looper support for oscillating said retainer, means independent of the looper support for moving said support for the retainer endwise, said means being constructed and timed so as to move said retainer lengthwise of the looper into engagement with the needle thread loop thereon, thence laterally, away from the looper to release the needle thread loop.

8. The combination of a work supporting arm, a looper shaft extending lengthwise thereof and adapted to oscillate and move endwise on said arm, a thread carrying looper rigidly fixed to the end of said looper supporting shaft, a supporting rod mounted in said work supporting arm and adapted to move endwise therein, a retainer mounted so

as to oscillate on said rod, said retainer including an elbow arm and a cam arm, and a controlling cam fixed to the looper shaft and located between said elbow arm and said cam

5 arm for positively oscillating said retainer.

9. The combination of a work supporting arm, a looper shaft extending lengthwise thereof and adapted to oscillate and move endwise on said arm, a thread carrying

10 looper rigidly fixed to the end of said looper supporting shaft, a supporting rod mounted in said work supporting arm and adapted to move endwise therein, a retainer mounted

15 so as to oscillate on said rod, said retainer including an elbow arm and a cam arm, a controlling cam fixed to the looper shaft and located between said elbow arm and said cam

20 arm for oscillating said retainer, said controlling cam having an active part adapted to engage the cam arm for oscillating the retainer in one direction, and a concentric portion adapted to engage said cam arm and give a dwell to the retainer.

25 10. The combination of a work supporting arm, a looper shaft extending lengthwise thereof and adapted to oscillate and move endwise on said arm, a thread carrying looper rigidly fixed to the end of said

30 looper supporting shaft, a supporting rod mounted in said work supporting arm and adapted to move endwise therein, a retainer mounted so as to oscillate on said rod, said

35 retainer including an elbow arm and a cam arm, a controlling cam fixed to the looper shaft and located between said elbow arm and said cam arm for oscillating said retainer, said controlling cam having an active part adapted to engage the cam arm for os-

40 cillating the retainer in one direction, and a concentric portion adapted to engage said cam arm and give a dwell to the retainer, said controlling cam having an active part adapted to engage said elbow arm for os-

45 cillating the retainer in the opposite direc-

11. The combination of a thread carrying looper, a needle adapted to vibrate laterally in a plane substantially parallel with the plane of oscillation of the looper when entering the needle thread loop, a retainer, means for actuating said retainer for causing the same to engage the looper thread and needle thread loop and move the same laterally relative to the body of the looper so as to insure that the needle in both of its positions of reciprocation will pass between the looper thread and the needle thread loop, on the one hand, and the body of the looper on the other.

12. The combination of a thread carrying looper, a needle adapted to vibrate laterally in a plane substantially parallel with the plane of oscillation of the looper when entering the needle thread loop, a retainer, means for actuating said retainer for caus-

ing the same to engage the looper thread and needle thread loop and move the same laterally relative to the body of the looper so as to insure that the needle in both of its positions of reciprocation will pass between the looper thread and the needle thread loop, on the one hand, and the body of the looper on the other, said retainer having the face thereof engaging the threads curved away from the threads and positioned so that the inclination of the face of the retainer will urge the threads thereon away from the body of the looper.

13. The combination of a needle, a thread carrying looper cooperating therewith, a retainer disposed in a line substantially at

80 right angles to the body of the looper, means for actuating said retainer for caus-

ing the same to engage the looper thread and the needle thread loop and move the same laterally relative to the body of the

85 looper so as to insure that the needle will pass between the looper thread and the needle thread loop on the one hand, and the body of the looper on the other, said re-

90 tainer having the face thereof engaging the threads curved away from the threads and positioned so that the inclination of the face of the retainer will urge the threads thereon away from the body of the looper.

95 In testimony whereof, I affix my signature.

ARVID ERICSSON.
